(57) **CLAIM**

We claim the ornamental design for a head for weight-distributing hitch, as shown and described.

DESCRIPTION

FIG. 1 is a perspective view of a head for weight-distributing hitch showing my new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a second perspective view thereof; and,

FIG. 9 is a third perspective view thereof.

The broken lines illustrate portions of the head for weight-distributing hitch that form no part of the claimed design.
